CLAIM

The ornamental design for a mobile pallet jack reader, as shown and described.

DESCRIPTION

FIG. 1 is a top, perspective view of the mobile pallet jack reader, showing my new design; and

FIG. 2 is a front view thereof;

FIG. 3 is a back view thereof;

FIG. 4 is a top view thereof;

FIG. 5 is a bottom side view thereof;

FIG. 6 is a right side view thereof; and,

FIG. 7 is a left side view thereof.

The broken lines in the drawings depict portions of the mobile pallet jack reader that form no part of the claimed design.
